CONCRETE FORM

Alphonse Fernandez, Washington, D. C.

Application May 14, 1934, Serial No. 725,611

11 Claims. (Cl. 61—45)

- The invention relates to concrete forms having retaining walls for the concrete constructed from flanged plates bolted together. Such forms are used extensively in constructing tunnels, sewers, 5 water conduits, arches, wells, walls, etc., and have heretofore been constructed from rectangular plates each having two of its flanged edges disposed longitudinally of the form wall and its other edges at right angles to the length of said wall. 10 Form walls constructed in this way however, have been prone to sag, twist, warp, wave, etc., causing a great deal of trouble and inconvenience in aligning and holding them solidly. One object of my invention however, is to provide a new and improved construction which will provide a much stiffer and stronger form wall, said wall being effectively braced by having the flanges of the 15 separate plates or sections disposed obliquely of the wall. 20 Another object is to provide wall sections of improved construction for rigid substantially fluid-tight connection with each other. A further object is to provide novel stabilizers for the form wall or walls, readily adjustable to 25 accurately position and hold the same. In this connection, a further object is to provide the stabilizers with passages through which fluid concrete may be forced, for instance into the space 30 between a form wall and the wall of an excavation, or into the space between inner and outer form walls. Yet another object is to provide the stabilizers with means for holding the usual concrete reinforcements in place, greatly facilitating the anchorage of said reinforcements preparatory to 35 pouring or forcing the concrete. A still further object is to provide an improved construction which may be manufactured easily and inexpensively and may be rapidly and conveniently assembled wherever its use is required. 40 With the foregoing in view, the invention resides in the novel subject matter hereinafter described and claimed, description being accomplished by reference to the accompanying drawings. 45 These drawings for illustrative purposes show the invention embodied in a tubular form for constructing sewers, conduits, tunnels, etc., but it is to be understood that the invention is not restricted to a concrete form of this type. 50 Fig. 1 of the accompanying drawings is a combined section and elevation showing the outer tubular wall of the form held in place within an excavation by means of the stabilizers, showing the manner in which fluid concrete is forced 55 through the passages of these stabilizers into the

space between the form wall and the wall of the excavation, and illustrating a number of reinforcements for the concrete held by arms which project from the stabilizers.

Fig. 2 is a combined section and elevation 5 showing the inner tubular wall held centered within the outer tubular wall by the stabilizers, showing the manner of forcing fluid concrete into the space between the two walls, and illustrating reinforcements for this concrete held by some of 10 the arms carried by the stabilizers.

Figs. 3 and 4 are vertical transverse sectional views as indicated by lines 3—3 and 4—4 respectively of Figs. 1 and 2.

Fig. 5 is a detail sectional view showing one 15 manner in which the holding arms for the reinforcements may be connected with the stabilizers.

Fig. 6 is a view similar to Fig. 5 showing another way of connecting the arms with the 20 stabilizers.

Fig. 7 is a detail sectional view showing one 25 of the manner types of feet with which the outer ends of the stabilizers may be equipped, according to the character of the material which they must abut.

Fig. 8 is an inner side elevation on an enlarged 30 scale showing a portion of one of the form walls and illustrating the oblique positioning of the flanges on the edges of the various plates or sections.

Fig. 9 is a view similar to Fig. 8 but showing a 35 different form of construction.

Fig. 10 is a disassembled perspective view showing one of the form sections shown in Fig. 9 and portions of two other sections in juxtaposition. 40

Figs. 11 and 12 are views similar to Fig. 10 but showing slight variations.

Fig. 13 is a perspective view showing the plate 45 from which the sections of Figs. 9 and 10 may be stamped.

In the drawings above briefly described, E denotes the wall of an excavation, O has reference to the outer tubular wall of the concrete form, C denotes the concrete between the walls E and O, I has reference to the inner tubular wall of the 50 mold and C' indicates the concrete between the form walls O and I. These two form walls are constructed in the same manner and a description of the outer wall O will suffice for both.

The wall O is formed from a plurality of polygonal plates or sections S, each of which is preferably diamond-shaped, each plate or section being given the requisite longitudinal curvature, having its two acute angular ends disposed at the 55 two extremities of said curvature and having its

obtuse angular corners disposed at opposite sides of a line extending between said acute angular corners. All edges of the plates or sections S are formed with marginal flanges 15 and the flanges 5 of said plates or sections are tightly secured together by bolts 16 or if desired, by other fastening means. The plates or sections S are so assembled that the flanges 15 along two edges thereof extend on lines oblique to the wall O and 10 the other flanges of said plates or sections also extend obliquely of the wall but on lines crossing the first named lines. By having the plates or sections abut on those oblique lines and positioning their flanges on said lines, the entire wall is 15 much more rigidly braced than when using the conventional construction. Moreover, the individual plates or sections possess a greater degree of inherent rigidity. This may be increased if desired, by forming said plates or sections with 20 stamped out X-shaped reinforcements 17.

In Figs. 9 and 10, the sections S' are similar to the sections S but possess additional structural characteristics. Each plate or section S' is formed with two short parallel longitudinal 25 edges 18 and with four relatively long edges 19 which converge from the ends of said edges 18 to form acute angular pointed ends for the plate or section. These plates or sections may well be each formed from a blank such as that shown in 30 Fig. 13, said blank having two slits 20 near two of its edges 19 and opening through the other two edges 19 respectively. The edge portions of the blank are bent laterally on the dotted lines 21 to provide the form plate or section with marginal flanges 22. The portions of these flanges which originally lay between the slits 20 and the blank edges parallel to said slits, which portions are denoted at 23, constitute tongues which project from the pointed ends of the plate or section 35 40 S', said tongues being disposed at opposite sides of the longitudinal center line of said plate or section. The flange ends 24 at the inner extremities of the tongues 23 constitute abrupt shoulders for a purpose to appear. The flanges 45 and tongues are all formed with bolt holes 25.

When the sections S' are assembled, the tongues 23 of the sections which are disposed end to end, overlap each other as shown in Fig. 9, and the portions 22' of the flanges 22, lie against the 50 overlapped tongues. Moreover, the tongues 23 abut the shoulders 24. Relatively long bolts 26 pass through the portions 23 and 22' and secure them tightly together, and additional bolts 27 pass through the abutting flanges 22 at other desired points. Exceptionally rigid, substantially fluid-tight joints are thus provided between the various plates or sections of the form.

In Fig. 11, the plates or sections S² are identical with the sections S' with the exception that 60 their tongues 23' are provided with projecting lugs 28 and the shoulders 24' are formed with notches 29. The lugs 28 and notches 29 interfit when the sections are assembled, providing a still more rigid structure.

65 The sections or plates S³ of Fig. 12 are identical with the sections S' except that their tongues 23'' are beveled at 30 and their shoulders 24'' are similarly beveled.

Some of the plates or sections S are formed 70 with openings 31 through which stabilizers 32 are threaded, said stabilizers being preferably similar to bolts. The outer ends of these stabilizers are intended to abut the wall of the excavation E and they may be shaped in any suitable way according to the character of the ma-

terial which they must abut. In most of the figures, the stabilizers are provided with substantially flat heads 33 at their outer ends but in Fig. 7, a foot 33' in the form of a flanged pan is shown which is intended to more effectively and anti-slippingly engage clay or other relatively soft material. The foot 33' is preferably formed with perforations 34 through which the concrete C may pass, for this foot and the projecting portions of the stabilizer 32 of course remains 10 in said concrete. The same is true of all of the stabilizers regardless of how their outer ends may be shaped.

All of the stabilizers 32 are formed with passages through which fluid concrete may be forced 15 into the space between the excavation wall E and the outer form wall O. For illustrative purposes, I have shown each stabilizer formed with a central bore 35 and with lateral outlets 36 from the outer end of said bore to conduct the concrete into said space between E and O. I have also shown each stabilizer 32 formed with additional outlets 37 within the confines of the outer wall O, these outlets 37 being closed by plugs or the like 38 when the concrete C is being forced 25 into place. The inner ends of some or all of the stabilizers 32 are provided with suitable means 39 whereby the usual concrete supply hose 40 may be coupled thereto.

A suitable end ring R is of course used while 30 forcing the concrete C into place, and the wall O will necessarily include triangular end sections R' to tightly abut said ring.

The stabilizers 32 hold the outer wall O accurately positioned and in the present showing, I 35 provide short tubular stabilizer sections 41 which may be threaded upon the inner ends of said stabilizers 32 to abut the inner wall I for the purpose of holding the latter in accurately spaced relation with the wall O preparatory to 40 forcing the concrete C' into place. Certain sections of this inner wall I are formed with openings 42 with which the hose 40 may be connected to force the concrete C' into place. Should any of these openings be aligned with the tubular 45 stabilizer sections 41 as seen for instance in Figs. 2 and 4, the concrete will enter the stabilizers and will escape through the openings 37 and through other openings 43 formed in said tubular sections 41, the plugs 38 being, of course, removed from the openings 37 when they have 50 served their purpose.

The stabilizers are provided with means for holding reinforcing rods or other concrete reinforcements in place, rods 44 being shown for 55 illustrative purposes. The means in question preferably consists of arms 45 projecting from the stabilizers, some at the exterior of the wall O and others at the interior thereof, the outer ends of said arms being provided with hooks 60 46 or with any other preferred formations to engage the reinforcements 44. The inner ends of the arms 45 may be threaded into sockets 47 in the stabilizers 32 as seen in Fig. 5 or said arms may be secured to collars 48 threaded upon said stabilizers as illustrated in Fig. 6.

It will be seen from the foregoing that novel and advantageous provision has been made for carrying out the objects of the invention and 70 while the general construction shown and described may be considered as preferred, it is to be understood that numerous variations may be made within the scope of the invention as claimed.

I claim:

1. In a sectional concrete form having an outer sectional wall for disposition in a tunnel or other excavation, and an inner sectional wall for disposition within said outer wall; stabilizing means for said inner and outer walls, said stabilizing means consisting of stabilizing portions threaded through the outer form wall and adjustable from the interior of said outer form wall to abut the excavation wall to hold said outer form wall in place, and stabilizing portions carried by one of said form walls to abut the other form wall and hold the two form walls in properly spaced relation. 10
- 15 2. In a sectional concrete form having an outer sectional wall for disposition in a tunnel or other excavation, and an inner sectional wall for disposition within said outer wall; stabilizers threaded through said outer form wall to abut the excavation wall and hold said outer form wall in place, and additional stabilizers having threaded engagement with the inner ends of the first named stabilizers and adapted to abut the inner form wall to hold the latter in place. 20
- 25 3. In a sectional concrete form for disposition in a tunnel or other excavation; stabilizers passing from the interior to the exterior of said form to abut the wall of the excavation and hold the form in place, said stabilizers having passages through which fluid concrete may be forced into the space between the form and the excavation wall. 30
- 35 4. In a sectional concrete form having inner and outer sectional walls; stabilizers extending between said walls to hold them in properly spaced relation, said stabilizers having passages through which fluid concrete may be forced into the space between the two walls. 40
- 45 5. A concrete form section comprising a plate having two short parallel longitudinal edges, and four relatively long edges which extend from the ends of said short edges and converge to provide pointed ends for the plate, all of said edges having apertured flanges, and apertured tongues integral with certain of said flanges and projecting longitudinally from said pointed ends of the plate. 45
- 50 6. A structure as specified in claim 5; said plate having lateral shoulders at the inner ends of said tongues, the outer ends of said tongues of the one plate being adapted to abut the shoulders of other plates and vice versa. 50
7. A structure as specified in claim 5; said plate having lateral shoulders at the inner ends of said tongues, the outer ends of said tongues of the one plate being adapted to abut the shoulders of other plates and vice versa. 5
8. A structure as specified in claim 5; said plate having lateral shoulders at the inner ends of said tongues, the outer ends of said tongues of the one plate being adapted to abut the shoulders of other plates and vice versa, the outer ends of said tongues being provided with integral lugs projecting longitudinally therefrom, said shoulders having notches of substantially the same size as said lugs to allow the tongue lugs of one plate to engage the shoulder lugs of other plates and vice versa. 10
9. A concrete form for reception in an excavation, said form having an opening, and a stabilizer threaded through said opening and adjustable from the interior of said form to dispose the outer end of said stabilizer in solid abutting contact with the excavation wall, said stabilizer having a longitudinal passage through which fluid concrete may be forced, said passage having an inlet end at the interior of said form and having a lateral discharge end at the exterior of said form. 20
10. An excavation liner comprising an outer sectional metal wall spaced inwardly from the excavation wall, an inner sectional metal wall spaced inwardly from said outer wall, concrete filling the space between said outer wall and said excavation wall and the space between said inner and outer walls, and radially disposed stabilizers passing through said outer metal wall, said stabilizers being embedded in said concrete and having their outer and inner ends abutting said excavation wall and said inner metal wall respectively. 30
11. An excavation liner comprising a sectional metal wall spaced inwardly from the excavation wall, concrete filling the space between said sectional metal wall and said excavation wall, additional concrete against and covering the inner side of said sectional metal wall, and radial stabilizers passing through said sectional metal wall and embedded in said concrete, the outer ends of said stabilizers abutting said excavation wall. 40

ALPHONSE FERNANDEZ.
